Specification of Letters Patent. Patented June 21, 1921.

Application filed March 12, 1920. Serial No. 365,358.

To all whom it may concern:

Be it known that I, GEORGE R. PYPER, citizen of the United States, residing at Salt Lake City, in the county of Salt Lake and 5 State of Utah, have invented new and useful Improvements in Signs, of which the following is a specification.

My invention is concerned with animated signs, and is designed to produce a novel 10 apparatus employing a method for animating signs wherein there is produced the appearance of the filling or emptying of a receptacle, or the emptying of one receptacle into another, and that without the employment 15 of a large number of individual lights and switching mechanism whereby they can be flashed on or off in a certain predetermined order and manner that has heretofore been found necessary to produce the 20 illusion.

In carrying out my novel method, a generally opaque screen plate is provided having the receptacle with its maximum contents outlined by perforations or small translucent portions (the perforations for liquid contents being arranged in horizontal rows) illuminated from the rear by one or more powerful lights, and the appearance of emptying a receptacle is produced by automatically 25 moving an opaque shutter between the light and the perforations representing the contents so as to cut off one row of perforations after another from the illumination from the top downward. In producing the appearance of filling, the movement of the shutter will necessarily be so as to permit the illumination of successive rows of perforations representing the contents upward, and where the apparent emptying 30 of one receptacle fills another, the pair of shutters must be connected or so operated in synchronism that one cuts off the perforations representing the contents from the emptying receptacle at the same rate that 35 the other permits the illumination of the perforations representing the contents of the receptacle being filled, and I may also provide a connecting set of perforations from the receptacle being emptied to the receptacle being filled, together with a rotated slotted 40 animating disk so as to produce the effect of the contents filling from one receptacle into the other.

To illustrate my invention, I annex hereto 45 a sheet of drawings in which the same refer-

ence characters represent identical parts in all the figures, of which—

Figure 1 is a front elevation of a sign employing my invention and showing the contents of a bottle being emptied into a 60 glass;

Fig. 2 is a rear elevation of the same with the rear wall of the casing removed; and

Fig. 3 is a plan view in section on the line 6-6 of Fig. 2. 65

The front plate 54 of the casing, or the "screen plate" as it is ordinarily designated, will have the bottle outlined by a series of perforations 55 therethrough, which perforations are covered from the rear by a channel 57 secured to the rear of the screen plate and having mounted therein a series of small spaced incandescent lights 58 which may always be illuminated, unless it is desired to flash the sign completely on and off, in which 75 case customary flashing mechanism will be employed. The glass into which the contents of the bottle are shown as being emptied is outlined by the perforations 56, which are likewise inclosed in a channel secured to 80 the rear of the screen plate 54 similar to the channel 57 and like it illuminated by small spaced incandescent lights contained therein.

The maximum contents of the bottle are outlined by the series of horizontal rows of 85 perforations 59, which are preferably rendered very translucent by securing on the back of the screen plate the cover 85 of thin paper which may be white or any color which it is desired to give to the contents 90 of the bottle. The maximum contents of the glass is likewise indicated by a similar series of perforations 60, preferably similarly covered by the sheet of translucent material 85. Another set of perforations 61 of the 95 same character as the perforations 59 and 60 are shown as leading from the mouth of the bottle to the top of the glass and are similarly covered by the sheet 85.

To produce the desired animation of the 100 foregoing figures, the following apparatus and arrangement will be employed: The body of the casing is preferably divided by partitions into the three compartments 62, 63 and 64, which contain respectively perforations 59 representing the contents of the bottle, and the perforations 61 which represent the contents flowing from the bottle into the glass, and the perforation 60 which represents the contents of the glass. Supported 105 110

in the compartment 62 well back of the perforations 59 is one or more incandescent lights 77, preferably arranged in a horizontal row at about the height of the center of 5 the perforations 59. Similarly supported in the compartment 63 back of the central portion of perforations 61 is the incandescent light 78 and similarly supported in the compartment 64 back of the central portion of 10 the perforations 60 is the light 80. Mounted in the compartment 62, as by being fulcrumed at 66, is the shutter 65, which may have the counterweight 67 thereon, and which is shaped so that as it is swung downward on its pivot, its lower edge successively cuts off the rows of perforations 59 from the illumination of the lights 77. Journaled on a suitable bearing back of the channel for the glass is the shutter disk 70, 20 which has a considerable portion of the face thereof cut away so that the contents of the glass will be illuminated beginning from the bottom and extending upward as the cut away portion 81 rises during the rotation of 25 the disk in the direction indicated by the arrow. The effect of the contents falling from the bottle into the glass is produced by the animating disk 74, which is journaled on the stub shaft 73 in such a position that 30 the regular spiral slots 79 therein travel relative to the light 78 so that alternate waves of illumination and darkness pass in the general direction of the curve outlined by the perforations 61.

35 As a convenient method of moving these various animating members, I employ the small electric motor 76 supported in the compartment 63 and having a small pulley on its armature shaft connected by the belt 40 75 with a groove in the periphery of the disk 74, so that said disk is rotated at the proper speed to simulate the falling of the contents. To rotate the disk 70, I employ the crossed belt 71 connecting the small pulley 45 on the hub of the wheel 74 with the grooved periphery of the disk 70, and to swing the shutter 65, I employ the crank arm 69 secured on the hub of the disk 70 and connected by the link 68 with the shutter 50 65 at such a point that the complete rotation of the crank arm 69 will swing the shutter 65 down and back the desired distance. While a pleasing effect is produced by keeping the current on the lights 77, 78 55 and 80 constantly, I preferably arrange a flasher so that the current will be cut off during the time that the shutter 65 is rising.

60 While I have shown and described my invention as embodied in the form which I at present consider best adapted to carry out its purposes, it will be understood that it is capable of modifications, and that I do not desire to be limited in the interpretation of the following claims except as may 65 be necessitated by the state of the prior art.

What I claim as new and desire to secure by Letters Patent of the United States is:

1. In an animated sign, the combination with a generally opaque screen plate having a receptacle outlined thereon by artificial 70 illumination and series of relatively small, closely spaced light transmitting portions in the screen plate within the outlined receptacle and simulating when illuminated its contents, of a source of artificial illumination back of the light transmitting portions, a shutter mounted to move between the source of illumination and the light transmitting portions, and means for moving the shutter so as apparently to vary the contents 75 of the outlined receptacle.

2. In an animated sign, the combination with a generally opaque screen plate having a pair of receptacles outlined thereon by illumination and series of light transmitting 80 portions in the screen plate within both the outlined receptacles and outlining their contents, of a source of illumination back of each of these two series of light transmitting portions, a pair of shutters mounted to move 90 between the two sources of illumination and the two series of light transmitting portions, and means for moving the shutter for the receptacle being emptied downward and the shutter for the receptacle being filled upward so that the contents of one receptacle 95 appear to disappear from it and to appear in the other.

3. In an animated sign, the combination with a generally opaque screen plate having 100 a pair of receptacles outlined thereon by illumination and three series of light transmitting portions in the screen plate, one within each of the outlined receptacles and the third between the same, of a source of 105 illumination back of each of the three series of light transmitting portions, a pair of shutters mounted to move, one each between its source of illumination and the light transmitting portions outlining the contents 110 of a receptacle, a slotted animating disk journaled back of the third series, and means for moving the shutter for the receptacle being emptied downward at the same time the shutter for the receptacle being filled is 115 moved upward, and rotating the animating disk to produce the appearance of the falling of the contents from the receptacle being emptied to the receptacle being filled.

4. In an animated sign, the combination 120 with a generally opaque screen plate having a pair of receptacles outlined thereon by illumination and three series of light transmitting portions in the screen plate, one within each of the outlined receptacles and 125 the third between the same, of a source of illumination back of each of the three series of light transmitting portions, a pair of shutters mounted to move, one each between its source of illumination and the light 130

transmitting portions outlining the contents of a receptacle, a slotted animating disk journaled back of the third series, and means for moving the shutter for the receptacle being emptied downward at the same time the shutter for the receptacle being filled is moved upward, and rotating the animating disk to produce the appearance of the falling of the contents from the receptacle being emptied to the receptacle being filled, said means consisting of a crossed belt connecting the hub of the animating disk with the periphery of the circular shutter for the receptacle being filled and a link connecting a crank arm of the hub of the last mentioned shutter with the shutter of the receptacle being emptied.

5. In an animated sign, the combination with a generally opaque screen plate having

a pair of receptacles outlined thereon by 20 illumination and three series of light transmitting portions in the screen plate, one within each of said receptacles and outlining its contents and the third between said receptacles, a casing back of the screen plate 25 having partitions dividing it into a space for each of the three series of light transmitting portions, a source of illumination within each of the three spaces or compartments, a swinging shutter mounted in each 30 of the compartments for the receptacles between a source of illumination and the light transmitting portions, a slotted animating disk mounted to rotate in the compartment for the connecting light transmitting portions, and means for swinging said shutters and rotating said disk.

GEORGE R. PYPER.
